DESIGN.

—o—

G. S. HENSEL.
TRIMMING.

No. 19,459.

Patented Dec. 3, 1889.

UNITED STATES PATENT OFFICE.

GEORGE S. HENSEL, OF PHILADELPHIA, PENNSYLVANIA, ASSIGNOR TO
THE HENSEL, COLLADAY COMPANY, OF PENNSYLVANIA.

DESIGN FOR TRIMMING.

SPECIFICATION forming part of Design No. 19,459, dated December 3, 1889.

Application filed October 21, 1889. Serial No. 327,720. Term of patent 7 years.

To all whom it may concern:

Be it known that I, GEORGE S. HENSEL, a citizen of the United States, residing in the city and county of Philadelphia, State of Pennsylvania, have invented and produced a new and original Design for Upholstery and Shade Trimmings, of which the following is a specification, reference being had to the accompanying photograph, forming part thereof.

The leading feature of my design for upholstery and shade trimming is a head with festoons, one within the other, and balls on said festoons, the said festoons being secured or looped at the same points on the head, and the balls or pendants having a smooth appearance and being in parallel rows.

In the photograph, A designates the head of the trimming, from which depend festoons B, which are in rows, one within the other, with balls C thereon. The ends of the festoons are attached to the head at substantially the same points, so that the rows of festoons and loops are parallel.

What I claim is—

A design for upholstery and shade trimming, substantially as shown and described.

GEORGE S. HENSEL.
